UNITED STATES PATENT OFFICE.

RICHARD K. HOHMANN, OF BELVIDERE, ILLINOIS.

TENSION-RELEASE, THREAD HOLDER, AND CUTTER.

1,182,273.

Specification of Letters Patent.

Patented May 9, 1916.

Application filed July 1, 1915. Serial No. 37,553.

To all whom it may concern:

Be it known that I, RICHARD K. HOHMANN, a citizen of the United States, and resident of Belvidere, county of Boone, State of Illinois, have invented certain new and useful Improvements in Tension-Release, Thread Holders, and Cutters, of which the following is a specification.

This invention relates to sewing machines and has particular reference to means for holding the thread at the time that the operator has finished one piece of work and changes to a new piece.

It includes means for controlling the tension on the thread and also means for gripping and holding the thread to prevent the needle from becoming accidentally unthreaded and in order to supply sufficient thread for the first stitch when the new material is being operated on.

According to the invention the tension mechanism is disabled, or in other words, the tension is removed from the thread as the presser bar carrying the presser foot is raised and the tension is not again applied to the threads until the needle bar approaches the lower limit of its downward movement. The thread is thus free and has no tension on it in making the first part of the first stitch. According to my invention, furthermore, there is provided means for gripping the free end of the thread on the lower part of the presser bar so as to hold it firmly after the presser bar has been raised and the machine is not in operation and this gripping means is released by the downward movement of the needle bar at substantially the same time that the tension is again applied.

The novel features of the invention will be apparent from the following description taken in connection with the drawings.

In the drawings, Figure 1 is a face view of the head of a sewing machine partly broken away showing an embodiment of my invention; Fig. 2 is a similar view with the parts in a different operative position; Fig. 3 is also a similar view with the parts in still another position; Fig. 4 is an enlarged detail view of a portion of the presser bar with the parts carried thereby; Fig. 5 is an enlarged detail view of a portion of the presser bar showing the gripping mechanism at right angles to what is shown in Fig. 4; Fig. 6 is a vertical section through the presser bar on the line 6-6 of Fig. 5;

Fig. 7 is an enlarged detail view of the gripping mechanism on the lower part of the presser bar; and Fig. 8 is an enlarged sectional view of the tension mechanism.

In the drawings I have illustrated the head 10 of a sewing machine which may be the ordinary shape or style and within which the needle bar, presser foot and other operating mechanism are included. It will be understood that the needle bar 11 is operated by a link 12 pivoted to the disk 13 which is carried on the end of the rotary shaft 14 driven in the usual manner. A sliding block 15 is secured to the needle bar at its upper end and travels in the guideway 16 so as to keep it in proper alignment. The presser bar 17 carries at its lower end the usual presser foot 18 and the link 19 pivoted at 20 bears on its upper end and is pushed downward by the spring pressed plunger 21. The presser bar 17 is raised in the usual manner by the lifter 22 having the handle 23. On the face plate 24 of the head 10 tension mechanism 25 is placed and as shown in Fig. 8 this tension mechanism embodies the plate 26 and the movable plate 27 pressed inward by the spring 28 surrounding the shaft 29 which has a projection 30 extending inside of the face plate 24. A pivoted lever 31 is secured to the fixed part of the frame and one end of it is made with an inclined surface immediately above the end of the projection 30. When the lever 31 is turned on its pivot the inclined face presses on the projection 30, thus moving the pin 29 and the plate 27 away from the plate 26, thus releasing the tension.

The lever 31 which disables the tension, as above indicated, is operated when the presser bar 17 is raised. When the lifter 22 is turned to raise the presser bar it raises the sliding member 32 which has at its lower end a foot 33 extending outward over the upper end of the lifter 22. This sliding member 32 has a horizontal part 34 at the top which bears against the under surface of the part 35 which is pressed downward by the coil spring 36 surrounding the upper part of the presser bar. The part 35 has secured to it the downwardly extending part 37 which is provided with an opening 38 through which the end of the lever 31 extends. When therefore the part 32 is lifted by the act of lifting the presser bar, the lever 31 is engaged by the depending part 37 and is turned on its pivot so as to

disable the tension mechanism as above indicated. The part 37 has secured to it a leaf spring 39 which has at its lower end an offset shoulder 40 and when the part 37 is 5 raised this offset shoulder engages the upper corner of the sleeve 41 in which the needle bar slides and which forms a fixed part of the machine. When the spring 39 is thus in engagement with the upper edge of 10 the sleeve it will hold the part 35 in upper position, thus holding the tension mechanism in inoperative or disabled condition. The presser bar 17 may then be lowered without lowering the part 35 since it will 15 still be supported by spring 39. When the needle bar descends in the next operation of the machine the lower corner of the sliding block 15 will engage the inclined surface of the spring 39 as the needle reaches the lower 20 limit of its movement and will disengage that spring from the top of the sleeve 41 and thus allow the parts to descend under the force of gravity and the influence of the spring 36. When they descend the pivoted 25 lever 31 will be turned out of engagement with the projection 30 and thus the tension will again be applied to the thread.

On the lower part of the presser bar I mount the clamping mechanism 42 and this 30 mechanism, as shown in Fig. 7, being secured to the presser bar 17, by means of the screw 43, and it embodies a fixed member 44 and a pivoted member 45, the jaws of which two members are yieldingly pressed 35 together. The part 45 is pivoted at 46 and has a cut-away portion along which the spring wire 47 extends. This spring wire when pressing against the side of the plunger 48 tends to keep the two members 44 and 40 45 together so as to clamp the thread between them. The plunger 48 extends parallel to the presser bar 17 for some distance above the gripping means 42 and is then bent outward and engages the lower 45 end of the vertically sliding member 32 at 49, so that it will be lifted as the part 32 moves upward. This plunger 48 has a notch 50 cut in its side so that when the plunger is at its lowest position this notch 50 will be opposite the spring wire 47 and that wire will enter the notch, thus relieving the pressure on the clamping members 44 and 45, as shown particularly in Fig. 6. It will be observed that the bend 51 of the plunger 55 48 is immediately below the lower end of the part 37 so that it will be pressed downward by that part as it moves in a downward direction.

In connection with the clamping members 60 44 and 45 I make use of a knife 52 across which the free end of the thread may be drawn to sever it when the operator has finished with one piece of work. The knife or thread cutter 52 and the clamping jaws 42 and 45 are mounted on the same bracket

which is secured to the presser bar 17 and the cutting edge of the knife 52 extends transversely of the planes of the opposed faces of the clamping members 44 and 45.

From the above description it will be apparent that in operation the tension on the thread will be released when the presser foot is raised and the thread will be gripped and held by the gripping means 42 so that the needle will not be likely to become unthreaded before the operation is commenced on another piece of goods. When the next operation is commenced tension will not be on the thread until the needle has almost completed its downward stroke in the first 75 stitch. It is well known that where the tension is on the thread at the beginning of the needle frequently becomes unthreaded because there is not sufficient friction to draw the thread through the tension mechanism and it will consequently be drawn through the needle eye in case the needle bar is not in its highest position when the preceding work is finished. It will further be observed that the operation of the tension and gripping mechanism is automatic.

Having described my invention what I claim and desire to secure by Letters-Patent is:

1. In a sewing machine, the combination 95 with a needle bar, of tension mechanism, means for disabling said tension mechanism and means operated by the needle bar as it descends to restore said tension mechanism to operative condition.

2. In a sewing machine, the combination with a needle bar, of tension mechanism, means for disabling said tension mechanism, a catch for holding said tension mechanism in disabled condition, and means 105 operated by the needle bar as it descends to release said catch and restore said tension mechanism to operative condition.

3. In a sewing machine, the combination 110 with a presser bar, of means for raising it, a needle bar, tension mechanism, means for automatically disabling said tension mechanism as the presser bar is raised, and means for automatically restoring said tension mechanism to operative condition as the 115 needle bar descends.

4. In a sewing machine, the combination with a presser bar, of means for raising it, a needle bar, tension mechanism, means normally inactive on the lower part of said presser bar for gripping the thread, means for automatically disabling said tension mechanism and bringing said gripping mechanism into operative condition as the presser bar is raised to its upper position, and means for automatically restoring said tension mechanism to operative condition as the needle bar descends, and means for disabling said gripping mechanism.

5. In a sewing machine, the combination 130

- with a presser bar, of means for raising it, a needle bar, tension mechanism, means operated by the presser bar as it is raised to its upper position to disable said tension mechanism, a catch for retaining said tension mechanism in disabled condition, and means operated by the needle bar in its descent for releasing said catch and restoring said tension mechanism.
6. In a sewing machine, the combination with a presser bar, of means for raising it, tension mechanism comprising spring pressed members, means carried by said presser bar for separating said members to release the tension as the presser bar approaches its upper position, and releasable means for maintaining said members in separated position.
7. In a sewing machine, the combination with a presser bar, a needle bar, of means for raising it, means on the lower part of said presser bar for gripping the thread, means for rendering said gripping means operative when the presser bar is raised, and means for rendering said gripping means inoperative when the needle bar descends.
8. In a sewing machine, the combination of a presser bar, tension mechanism, a lifter for raising the presser bar and simultaneously operating said tension mechanism to release the tension on the thread, and means to keep the tension mechanism released when said lifter is operated to lower the presser bar.
9. In a sewing machine, the combination of a presser bar, a needle bar, tension mechanism, a lifter for raising the presser bar and simultaneously operating said tension mechanism to release the tension, means for reciprocating said needle bar vertically, and means whereby the tension mechanism is restored to operative condition when the needle bar has almost completed the next downward stroke after the presser bar has been lowered.
10. In a sewing machine, the combination of a presser bar, a needle bar, means for reciprocating said needle bar, tension mechanism, a lever for raising the presser bar and simultaneously operating said tension mechanism to release the tension, means whereby said tension mechanism may be kept released while said needle bar is raised and after said lever is operated to lower the presser bar, and means whereby the tension mechanism is rendered operative when the needle bar descends.
11. In a sewing machine, the combination of a presser bar, a needle bar, means for reciprocating said needle bar, tension mechanism, thread gripping mechanism, independent of said tension mechanism, means for raising said presser bar and simultaneously actuating said tension and gripping mechanisms when the needle bar is in raised position, so as to release the tension and grip the thread when the presser bar and needle bar are raised, and means whereby the tension mechanism and gripping mechanism are operated when the needle bar descends, so as to set the tension and release the hold of the gripping mechanism.
12. In a sewing machine, the combination with a needle bar, of means for actuating the same, a normally inactive thread gripping device, means for setting said gripping device to grip the thread and means for automatically operating said device to render it inactive and release the thread when the needle bar descends.
13. In a sewing machine, the combination of a presser bar, a needle bar, means for actuating said needle bar, means for lifting said presser bar, normally inactive gripping means rendered operative to grip the thread when said presser bar is lifted, a catch for retaining the gripping means in gripping position and means operated by the needle bar in its descent for releasing said catch and restoring said gripping mechanism to its normally inactive position.
14. In a sewing machine, the combination of a presser bar, a needle bar, a normally inactive gripping device mounted on said presser bar, means for lifting said presser bar and gripping device and rendering the gripping device operative to grip thread, and means whereby the gripping device is maintained in its gripping condition until after the presser bar is lowered and means operated by the needle bar as it descends to restore the gripping device to its normal and inactive condition.
15. In a sewing machine, the combination of a presser bar, a needle bar, a normally inactive thread gripping device, means for raising the presser bar and simultaneously causing said gripping device to operate to grip the thread, means to prevent the operation of said gripping device when the presser bar is lowered, and means for restoring the gripping device to its normally inactive condition when the needle bar descends.
16. In a sewing machine, the combination of a head or casing, a presser bar and a needle bar projecting out of the casing, a normally inactive gripping device outside the casing near the outer end of the needle bar, means for raising the presser bar and simultaneously actuating said gripping device to grip the thread, means for retaining said gripping device in gripping condition, and means operated by the needle bar in its descent for restoring said gripping device to its inactive condition.
17. In a sewing machine, the combination of a presser bar, a needle bar, a gripping device, a tension device, a member slideable along the presser bar, a lever for lifting said

- slidable member and the presser bar, a connection between said slidable member and gripping device to actuate the latter, means whereby the tension device is actuated when 5 the slidable member is raised, a spring catch associated with said slidable member and adapted to retain the tension device in released condition and to retain the gripping device in gripping condition when said lever 10 is operated to lower the presser bar and a device movable with the needle bar adapted to disengage said spring catch to release said slidable member to set said tension device and restore said gripping device to inoperative 15 condition.
18. In a sewing machine the combination of a presser bar having a presser foot, a normally inactive thread clamping device comprising two substantially similar cooperating 20 jaws mounted on said presser bar above the presser foot, means for raising the presser bar and simultaneously actuating said clamping device, and a thread cutter carried by said presser bar and associated 25 with the clamping device.
19. In a sewing machine, the combination of a presser bar, thread gripping means comprising a bracket mounted on said presser bar and a pair of jaws mounted on said 30 bracket and adapted to grip the thread between them, means for raising the presser
- bar, and means whereby one of the jaws is moved relatively to the other to grip the thread when the presser bar is raised. 20. In a sewing machine, the combination 35 of a presser bar, thread gripping means comprising clamping members mounted on said presser bar and adapted to grip the thread between them, one of said clamping members being pivoted and having a resilient 40 member associated therewith, means for raising the presser bar, and means adapted to be actuated when the presser bar is raised to engage said resilient member and swing the pivoted clamping member to grip the thread 45 between said clamping members.
21. In a sewing machine, the combination of a presser bar, thread gripping means mounted on said presser bar and comprising a bracket secured to the presser bar and two 50 clamping members mounted on said bracket, said members having opposed faces adapted to grip the thread between them, means for raising the presser bar, means for actuating the thread gripping means, and a thread 55 cutter on said bracket and associated with the thread gripping means and having its cutting edge extending transversely of the planes of the opposed faces of said clamping members. 60

In testimony whereof I affix my signature.
RICHARD K. HOHMANN.
